UNITED STATES PATENT OFFICE.

ELEUTHERE PAUL DU PONT, OF MONTCHANIN, DELAWARE, ASSIGNOR TO DU PONT MOTORS, INCORPORATED, OF WILMINGTON, DELAWARE, A CORPORATION OF DELAWARE.

DESIGN FOR AN AUTOMOBILE BODY.

Application filed December 19, 1927. Serial No. 24,550. Term of patent 14 years.

To all whom it may concern:

Be it known that I, ELEUTHERE PAUL DU PONT, a citizen of the United States, residing in Montchanin, county of New Castle, State of Delaware, have invented a new, original, and ornamental Design for an Automobile Body, of which the following is a specification, reference being had to the accompanying drawing, which forms a part thereof.

Figure 1 is a side view of an automobile body embodying my design.

Figure 2 is a front end view of the automobile body shown in Figure 1.

Fig. 3 is a rear view of the automobile body as shown in Figure 1.

I claim:

The ornamental design for an automobile body as shown.

In testimony of which invention, I have hereunto set my hand, at Wilmington, Delaware, on this ninth day of December, A. D. 1927.

ELEUTHERE PAUL DU PONT.
